UNITED STATES PATENT OFFICE.

S. BOWEN TURPIN, OF WASHINGTON, DISTRICT OF COLUMBIA.

DESIGN FOR A HANDKERCHIEF.

SPECIFICATION forming part of Design No. 18,558, dated August 21, 1888.

Application filed July 9, 1888. Serial No. 270,470. Term of patent 3½ years.

To all whom it may concern:

Be it known that I, S. BOWEN TURPIN, a citizen of the United States, residing at Washington, District of Columbia, have invented 5 certain new and useful Improvements in Design for Handkerchiefs; and I do hereby declare the following to be a full, clear, and exact description of the invention, such as will enable others skilled in the art to which it appertains 10 to make and use the same.

The figure is a plan view of my original 15 design for handkerchiefs, representing the body portion and background and a rope in circular form connecting four circles placed at radial points, each circle being surmounted by a shield, from beneath which projects the representation of two pennants, which are usually colored. The representations of the 20 strands of the rope are of contrasting colors, respectively.

The center piece of this design is composed of three circles arranged in a triangular form, the lower part of the upper circle being cov-

ered by the upper part of the two lower ones. From behind the upper circle project two 25 flags or the representation of two flags of the United States. In the upper circle is the figure of an eagle, over which is a scroll containing words. Beneath the circles, in the center of the design, is a scroll also containing 30 words, the letters of which being in no particular type or form. In front of and in center of said lower scroll is a shield, as set forth in the accompanying drawing. The representation shows the figures of thirty-eight stars. 35

I claim—

The design for a handkerchief having the surface ornamentation substantially as shown and described.

In testimony whereof I affix my signature in 40 presence of two witnesses.

S. BOWEN TURPIN.
